UNITED STATES PATENT OFFICE

94,174

DESIGN FOR AN ENCASED MEAT LOAF

Charles H. Vogt, Philadelphia, Pa., assignor to
Modern Food Process Company, Philadelphia,
Pa., a corporation of Pennsylvania

Application July 13, 1934, Serial No. 52,580

Term of patent 14 years

To all whom it may concern:

Be it known, that I, Charles H. Vogt, a citizen of the United States, residing at Philadelphia, in the county of Philadelphia and State of Pennsylvania, have invented a new, original, and ornamental Design for an Encased Meat Loaf, of which the following is a specification, reference being had to the accompanying drawing, forming a part thereof:

Figure 1 is a perspective view of an encased meat loaf embodying my new design.

Figure 2 is a top plan view of the encased meat loaf shown in Figure 1.

Figure 3 is an end view of the encased meat loaf of Figure 1.

The dominant features of the design are the triangular form with well rounded side and end edges, and the parallel longitudinal grooves limited to the sides and terminating substantially short of the end edges, the side edges being free of grooves and the nearest groove to each side edge being substantially spaced from said edge.

I claim:

The ornamental design for an encased meat loaf substantially as shown and described.

CHARLES H. VOGT.
